UNITED STATES PATENT OFFICE.

JOHN ALBERT PROCTOR, OF REVERE, MASSACHUSETTS, ASSIGNOR TO WIRELESS SPECIALTY APPARATUS COMPANY OF BOSTON, MASSACHUSETTS, A CORPORATION OF NEW YORK.

SYSTEM OF WIRELESS COMMUNICATION.

1,194,066.

Specification of Letters Patent.

Patented Aug. 8, 1916.

Application filed July 3, 1912. Serial No. 707,414.

To all whom it may concern:

Be it known that I, JOHN ALBERT PROCTOR, a citizen of the United States of America, and a resident of Revere, Massachusetts, have invented certain new and useful Improvements in Systems of Wireless Communication, the principles of which are set forth in the following specification and accompanying drawing, which disclose 10 the form of the invention which I now consider to be the best of the various forms in which the principles of the invention may be embodied.

The inventions hereof relate to the transmission and reception of intelligence by electric ether waves, and more particularly to a system including a sender involving the employment of an electrical discharge in such way as to produce a single sharp blow, 20 all the energy of which is forthwith impressed by shock or impact upon the radiating conductor wherein it is left free to oscillate persistently until it is finally entirely radiated; and the invention relates 25 yet more particularly to a system including such a sender in combination with a receiver not only wave-tuned to the sender but also adjusted to the pure train-frequency now for the first time obtained by such sender. 30 In this system the action in the discharge or exciting circuit is such that after the occurrence of the sudden energy movement therein, and after the immediate transference of all such energy by impact to the 35 radiating conductor, there can be no continued oscillation of the energy in the exciting circuit. That is, the exciting circuit and its elements are so constructed, and the wave of electromotive force applied to 40 charge the condenser of the exciter circuit is of such form, and all the conditions in general are such, that "extra" or "partial" 45 irregular and harmful discharges or overtones are prevented, so that the action is 50 limited to regularly spaced and useful discharges, and substantially no energy is lost by heating, and in general the exciting circuit is a dead-beat circuit of maximum efficiency for its object of charging by impact or shock the radiating conductor, 55 which is caused to become a persistent oscillator by virtue of said novel action of the exciter circuit. The result of all this is two-fold. First, the radiating conductor is

caused to become a persistent oscillator because all the energy is isolated in it to oscillate therein until it is finally completely radiated, instead of being partially returned to and wasted in the exciting circuit. Second, the oscillations in the radiating conductor are limited to a single frequency because there is no reaction between the exciting circuit and the radiating conductor, to cause plural frequencies in the system. The result of the persistent oscillations in 65 the radiating conductor is the radiation of trains of electrical ether waves which are both persistent and of a single uniform wave frequency. The highly important advantage of this final result is the very 70 greatly increased efficiency of such waves in respect to their effect on a receiving conductor, particularly when the latter has the same natural frequency or periodicity as that of the waves, more particularly when 75 the frequency of occurrence of the wave-trains is high and the receiving station is adjusted to the same train-frequency, and yet more particularly when all the conditions exist which are disclosed herein. 80

The above objects are attained for the first time, as I believe, by the means and methods disclosed herein, although various attempts and unfulfilled claims have been made as to some of the same, in connection 85 with systems termed variously "quenched-spark" and "quenched-gap".

An important invention hereof is that of the means and methods of employing the potential for charging the condenser of the 90 exciting-circuit, in such wave form of electromotive force as prevents the occurrence of extra or partial discharges, and without resulting loss of efficiency. Such prevention is not only very important in general, in 95 contributing to the obtaining of the completely damped exciting circuit of my system, and as a part of any system wherein it is desirable to limit the action of the exciting circuit to regular discharges, but it is 100 particularly important in any case where there is employed a high degree of spark-frequency (*i. e.*, wave-train frequency), as is preferable, particularly where, as in my system, means are preferably employed for 105 giving the receiving station the same train-frequency as the ether waves, in combination with the means at the sending station

for producing in the radiating conductor persistent oscillation trains which have a pure train-frequency, *i. e.*, which are evenly spaced from each other. (Whether the train-frequency be of high or low degree, uniform spacing of the wave-trains, (*i. e.*, the occurrence of the trains at uniform time intervals) is essential to efficient train tuning at the receiver, but such train tuning is much more efficient, in proportion as the train frequency is higher.) Therefore this invention as to preventing extra discharges has at least two distant uses of importance which may be employed separately but which are advantageously employed together in a single system as disclosed hereinafter, *i. e.*, first, in making possible the production of a pure shock or impact system, and second, and in any system not necessarily an impact system, in making possible the production of a pure train-frequency of ether waves such that the efficiency is greatly increased by giving the receiver the same train-frequency as that of the ether waves.

Of the drawings, Figure 1 is a diagrammatic curve of the conditions of certain prior systems, showing the complex relation of energy and wave length, wherein only one portion of the energy of the ether waves can be efficiently received upon a receiving conductor; Figs. 2 and 3 are diagrams showing the action of different prior systems, which diagrams assist in making clear, by distinction, the action of the new system hereof, which action is shown diagrammatically in Figs. 4 and 4^A; Fig. 5 is a diagrammatic illustration of the construction and electrical winding of a generator which may be and preferably is employed in my new system as the means for developing the electromotive force in the form characteristic of my invention, to be impressed on the exciting circuit; Figs. 6 and 7 are diagrammatic representations respectively of the sending and receiving apparatus preferably employed in my system; and Fig. 8 is a diagrammatic representation of the action of the invention when employed to resonantly charge the condenser of the exciting circuit.

The prior art system which produced the conditions shown in Figs. 1 and 2 is obsolescent and is different from the prior art system which produces the conditions shown in Fig. 3, the latter system being the so-called "quenched-spark" system and constituting a crude attempt at accomplishing the object attained by my invention of the shock or impact system hereof.

The system of Figs. 1 and 2 is that characterized by a persistently oscillatory exciting circuit combined with a rapidly damped radiating circuit, the effect of which is indicated by the curve of Fig. 1, wherein the

ordinate is energy and the abscissa is ether wave-length. The curve shows the etheric wave conditions involving the relation between the wave-length and the energy. Two so-called "humps" occur, as shown. This condition is disadvantageous in various respects, including the difficulty and ordinarily the impracticability of usefully employing at the receiving station the energy of both humps. The conditions in the three sending circuits of said system are shown in Fig. 2, respectively at "Source" of energy or supply circuit, "Exciter" or condenser circuit and "Radiator" or antenna circuit. The showings are diagrammatic, particularly as to the spacing of waves and wave-groups, but in substance the conditions of best working efficiency are shown. The lowest curve, "Source," shows the potential which is impressed on the exciter circuit to charge the condenser thereof. The "exciter" curves illustrate the successive trains of oscillations in the exciter circuit, which result from the condenser discharges. (Here ideal conditions are indicated without consideration of the "extra discharges" which exist here as well as in the so-called quenched spark systems and which here simply serve to increase the inherent inefficiency of this system.) As is shown, each oscillation train starts at maximum and gradually tails off. The "radiator" curves show the successive trains of oscillations in the antenna or radiating conductor which result from the action of the exciting circuit and from the persistent reaction between that and the radiating circuit. As is shown, each train starts at minimum, gradually builds up to maximum and then yet more gradually tails off. All this precedes the ether conditions indicated in Fig. 1. The actual ether-waves produced correspond generally with the "radiator" oscillations, as to frequency and energy, but owing to their complexity they are not definitely and completely understood by physicists, and therefore, although their said characteristics are observable by the results at the receiving station, no attempt is here made to illustrate them.

The most serious defects of the above system are its large energy losses in the exciter and its inability to produce pure or uniform ether waves, *i. e.*, waves having a single wave-frequency. The reason is, briefly, that the structure of the exciter is such, that operating as a persistent oscillator, the oscillations induced by it on the radiator react on the exciter before the latter's oscillations die out and while they are yet acting on the radiator, so that not only is a considerable part of the energy of the reacting oscillations wasted in the dissipative resistances of the exciter, but the part of the total energy not wasted in the circuits sets up complex oscillations in the radiator

which result in ether wave-trains each having two or more frequencies or "humps," as indicated in Fig. 1. (No attempt has been made to show, at "Exciter," Fig. 2, the complex oscillations resulting therein from the reaction of the radiator circuit. The curves there shown are restricted to an ideal showing of the oscillations originally produced by the useful discharge, even eliminating the "extra discharges," as stated above.) Furthermore, in addition to the impracticality of usefully employing at a receiving station, the energy of both humps, the losses in the exciter decrease the lengths of the oscillation trains in the radiator, thereby damping it substantially and causing it to radiate correspondingly short trains of waves, resulting in reducing the ability to sharply wave-tune the receiving antenna, said damping being a defect which is cumulative with the impure wave-trains and resulting double-hump ether waves.

Similar defects in results, but from different causes, exist in the systems in which attempts have been made to obviate the defects of the above system. Such is the so-called "quenched-spark" system, the typical conditions in which are shown in Fig. 3. The most harmful action here is that of the "extra" or partial discharges in the "Exciter", (in the decrescent part of the potential curve, B, D, F) indicated at X, "Exciter". The useful discharges are indicated at U. In many cases there are several extra discharges X. These are not liable to occur during the rise of potential, because the discharge-gap is then, prior to the regular discharge, in a cool or non-conductive state. The effect of these extra discharges is to produce overtones or complex oscillation trains (as see curves of oscillation-trains at "Radiator", Fig. 3), having also impure train-frequencies, in turn producing ether waves having two or more wave-frequencies and impure train-frequencies, all as in the case of the system of Figs. 1 and 2, some of the disadvantages of which have been noted above. If the showing at "Radiator", Fig. 3, were continued out to the right, it would show the fact of unequal spacing between the oscillation trains, as well as unequal lengths of the oscillation-trains themselves, chiefly due to the variations and uncertainties of the spark-discharges. Also the extra discharges impair the purity of the sound in the telephones at the receiving station, by superimposing on the fundamental periodic note, a rustling or hissing non-musical sound, which indicates the non-efficiency of receiving.

At "Source", Fig. 3, the regular sine curve, A, B, D, F, etc., indicates the potential impressed on the exciter circuit, by an ordinary sine wave-form alternator. The regular and useful discharge is at B, C, this

being the initial break-down of voltage to zero by the condenser discharge, after which, (the discharge gap opening the circuit), the voltage again builds up along C. D. The harmful extra discharge or discharges (D, E, at "Source", and X at "Exciter"), occur as follows: The discharge-gap is set to break down before the peak of the potential wave, in order to be certain of at least the one useful discharge per half-cycle of said wave. The result is that the potential builds up again at the latest not far beyond the peak of the wave, and this insures at least one harmful extra discharge and frequently more. It has seemed impossible to prevent such discharges without materially reducing efficiency. All attempts to prevent them have not only failed but also have been accomplished by losses of efficiency. For example, symmetrical sharp-peaked potential waves have been tried, wherein the drop from maximum (being sharp like the rise to maximum) was so rapid that no extra discharge could occur; but this reduced the efficiency very materially by departing from the preferable sine form, which is essential for maximum efficiency for charging preparatory to the initial or useful discharge. Also attempts to prevent extra discharges have been made by the use of dissipative resistances, etc., which obviously reduce efficiency. Other attempts have been made, without success, involving accurate regulation of voltage and discharge-gap, with the object of causing the initial discharge to occur at the peak of the potential wave, and thereby reduce the period in which the extra discharge might occur. Such attempts not only were ineffectual in preventing extra discharges, but they failed to insure regularity of useful discharges, irregularity of which even without any extra discharges, results in a similar impurity of note to that caused by the occurrence of extra discharges, together with all the other disadvantages of extra discharges, as above enumerated.

In accordance with an important feature of this invention, indicated in Fig. 4, all the above serious defects and difficulties are effectively obviated, without the slightest reduction of efficiency, and permissively with the use of the efficient sine potential wave for condenser-charging. This is done by a very simple expedient, consisting merely in employing a special form of the part of the potential wave after the useful condenser-discharge has occurred, by means of which special wave-portion the regularity of useful discharges is insured and all extra discharges are made impossible, as has been demonstrated in practice.

This invention involves not merely preventing extra discharges without loss of efficiency in the sending circuits, but permits the employment of efficient co-operating re-

ceiving apparatus and the production of results which have never before been attained in any system, including more particularly the persistent oscillation of the radiator and 5 the limitation of the oscillations therein and of the ether waves radiated therefrom, to a single uniform wave frequency and a single uniform train-frequency, with all the resultant increase in the 10 efficiency of reception as compared with all prior systems, including the ability to give the receiver a train-frequency which is that of the single uniform train-frequency of the ether waves, and to employ 15 a single receiving circuit tuned to the single wave-frequency of the ether-waves.

The potential wave employed herein is preferably of sinusoidal form as to its portion (as see a part A, B of the half cycle, 20 "Source," Fig. 4) which is used to charge the condenser of the exciter circuit, this sine form being by far the most efficient form for that purpose. A subsequent part of the wave, however, (the rest of the half cycle in 25 the case shown at B, D, E, "Source," Fig. 4) is asymmetrical, *i. e.*, is steeper than the first or charging portion, constituting a departure from the symmetrical sine form or any other symmetrical form. That is, from the 30 point B, where the discharge-gap breaks down and the condenser discharges and causes the drop B, C to zero potential, the normal subsequent drop of the potential supplied from the source is so rapid or steep 35 that although, immediately after the discharge, the potential of the condenser rises again, as at C, D, yet it cannot possibly rise high enough to break down the discharge-gap again during the same half-cycle. The 40 result is the absolute prevention of extra discharges, and only the regular single useful discharge can possibly occur, as shown at U, at "Exciter," Fig. 4. This total elimination 45 of the extra discharges, such as at X, "Exciter," Fig. 3, prevents the production of overtones or complex oscillation trains and impure train-frequencies in the antenna, such as are shown at "Radiator," Fig. 3, which subsequently result in correspondingly complex and inefficient ether waves. The result 50 of the elimination of the extra discharges, in respect of the action of the antenna, is indicated at "Radiator," Fig. 4, where, as distinguished from the showing at "Radiator," Fig. 3, and the description thereof, the oscillation trains start at a maximum and continue persistently with a uniform decrement while they tail off very gradually. These trains are also always of substantially 55 uniform length, and have uniform, substantially equal, spacing between them, so that a pure train-frequency is attained which is uniform in all respects including both length of trains and spacing between trains. These 60 uniform trains, being free from the complex-

ties caused by extra discharges, and free from the reaction of the radiator on the exciter, produce pure single-humped ether-waves, as indicated in Fig. 4^A, Sheet 1, whereas in Fig. 1 showing the double-humped 70 wave of prior systems, the curve indicates the etheric wave conditions involving the relation between the wave-length and the energy. In respect of the "humps," a comparison of Figs. 1 and 4^A strikingly illustrates the difference between the results of the operation of my system and that of Fig. 1. Comparing the "exciter" curves of Figs. 2 and 4, the difference is also striking between the dead-beat exciter of my system 75 (Fig. 4), acting to charge the radiator by shock or impact, and the persistently oscillatory exciter circuit of the system of Fig. 2, wherein the charging of the radiator is correspondingly prolonged and involved in continued reaction with the exciter. The illustration, Fig. 2, is ideal and not exact by reason of the omission of the irregular action in the exciter caused by its continued reaction with the radiator; but this omission 80 serves to make more clear the distinction between my exciter and that of Fig. 2 above stated. Similarly striking is a comparison of the "radiator" curves of these Figs. 2 and 4, showing in my system (Fig. 4) the purity 85 and much greater persistence of the oscillation trains. In fact, the actual conditions in my "radiator" circuit resemble the showing of the "exciter" curves of the system of Fig. 2, the remarkable point being that in 90 my case the persistent oscillation trains occur in the antenna or radiator instead of in the "exciter" circuit as in the system of Fig. 2. In all these curve diagrams, the showings 95 are largely diagrammatic, but the relative 100 showings of the different systems are not only fair, but the prior systems have been favored in their showings by limiting the same to their best possible operating conditions. In my system the persistency of the 105 oscillations in the "Radiator," Fig. 4, will be appreciated from the statement of the fact that in the case here illustrated, the inactive 110 time between oscillation trains is only about the same as the length of a train itself. In 115 "Radiator," Fig. 4 the wave-spacing is to scale, although the wave-amplitude and shape of wave-crests is somewhat diagrammatic. The case selected for illustration has the following data: flat-top antenna, with 120 center of capacity of horizontal portion 200 feet above the ground. Electrostatic capacity of antenna is .002 microfarad. Wave-length is 1200 meters. Total inductance in antenna circuit is 203 microhenries. Total 125 resistance, (including radiation resistance) is 4.1 ohms. Decrement is .04. One hundred and fifteen oscillations before reduction to one per cent. of the initial amplitude. Each 130 of the oscillation trains in "Radiator," Fig.

4, has a time period of over four hundred and fifty micro-seconds, this being also little less than the uniform inactive time between trains, which is less than five hundred and fifty micro-seconds. In fact, in this system, with wave-lengths longer than that indicated above, and consequently with lower decrement, the antenna oscillation trains may last a thousand micro-seconds or more, in which case the trains would meet or overlap, making the oscillations practically continuous. Although at "Radiator," Fig. 4, the persistency and purity of the oscillation trains themselves are clearly indicated, the fact that they are so extremely persistent has prevented an illustration of the uniformity of their recurrence, which is one of the most important results of the invention. In "Radiator," Fig. 4, where the oscillation-spacing or frequency is to scale, and where are shown all the many oscillations of one of the uniformly recurring and persistent oscillation trains, it has been impossible, within the limits of the sheet, to make a clear, fair-sized showing of a complete train and also to show a plurality of trains including the uniform time spacing between their occurrence.

When it is stated herein that the space or time between trains is uniform, what is meant is the time between the beginning or occurrence of one train and the beginning or occurrence of the next, and that in the case of any given sender, the timing or spacing is the same throughout the entire series of trains constituting a signal and producing a single note at the receiver; all as distinguished from prior systems, where the train-spacing or frequency was irregular owing to the lack of control over the time of the discharges.

A preferred means for producing the gradually charging asymmetrical wave of potential, as above, and such as at "Source," Fig. 4, is shown in Fig. 5. In the specific example shown, such means consists of an alternating current generator of a special construction suitable for producing such waves, as by having a special arrangement of inter-poles to effect the modification of the formerly-employed symmetrical sine form shown in Fig. 3. There are various ways of producing the gradually charging asymmetrical wave-form of this invention, which ways include various forms of alternating current generators, and although the special generator disclosed is the one now preferred by me for commercial use, yet it is only one of the various forms of generators included within the invention; and although the employment of some special generator is now believed to be the preferred means, yet that is by no means the only way within the invention, of producing the desired special wave. I contemplate that, upon the disclosure

of my invention, it will be easy for one skilled in the art to design, or borrow from the prior art, various equivalent means for producing the special wave employed in accordance with my invention. Broadly, the desired wave is one which first approaches a maximum charging value, more gradually than its subsequent relatively sudden drop, (and preferably along a sinusoidal curve), and then drops sharply to the low value. It is this sharp drop after the maximum charging value to the low value, which eliminates the possibility of extra discharges. It is the substantial sinusoidal form up to the maximum charging value, which is of the greatest value in charging the condenser, as distinguished from a sharp or peaked wave. The fundamental advantage in the invention, irrespective of any precise sine form of wave, is the combination of the relatively slow or gradual charging part of the curve, up to substantially the maximum charging value, with the relatively rapid and sudden drop to low value after the discharge maximum. It is this combination wave or substantially asymmetrical potential wave with a gradual charging portion and a relatively sudden drop which I here define broadly as the gradually charging asymmetrical wave of the invention, without any limitation other than that the discharging part of the wave is more abrupt than the charging part up to the maximum charging value, although the preferred specific form of wave has a charging part which approaches as nearly as possible to a true sine form, as for one example, in Fig. 4; and it is this form which is produced by the machine diagrammed in Fig. 5 which illustrates the essentials of the mechanical construction and electrical windings of this particular means of producing the special potential wave. In Fig. 4 are shown one discharge per half-cycle, involving two separate charging portions of the curve per cycle; but in Fig. 8 is shown and will be described a case wherein there is only one discharge per cycle.

In Fig. 5 the armature "arm" rotates as per arrow and carries collector rings C^1 , C^2 from which the alternating current is taken off through the leads to the condenser or exciter circuit of the sending apparatus (see Fig. 6, where the special generator is at G).

In Fig. 5, four ordinary field poles are shown, N , S , N^1 , S^1 , their windings being supplied from a source of direct current through a rheostat X , as usual, their source of supply constituting the supply for the ordinary or regular field of the generator.

The armature includes the usual conductors, only one of which, Y , is shown, for simplicity's sake. The usual operation would be, (first considering the top north field pole N), that armature-conductor Y , approaching pole N , would have an electromotive force

force generated in it, which would become maximum when Y passed under pole N, and which would gradually decay as Y moved farther to the right, until the electromotive force reached zero when Y was half way to pole S, all as shown in the curve at "Source," Fig. 2, of prior systems.

The special construction of this generator, however, includes an extra or auxiliary set 10 of field poles s , n , s^1 , n^1 . (For simplicity's sake only four complete sets of pairs of poles are shown. In practice a greater number is used, depending on the discharge or train-frequency desired and the available speed of 15 the driver of the generator.) Each pole of these auxiliary poles is located near to a pole of the regular set N, S, N^1 , S^1 , and beyond it in the direction of rotation of the rotor "arm." Also each auxiliary pole is 20 magnetically of a sign opposite to that of its adjacent regular pole, as indicated by the reverse windings and by the reference letters N, S, n , s , for "north," "south," etc. The windings of the auxiliary poles are supplied 25 from a source of direct current through the rheostat X^1 .

The above construction modifies the ordinary action in this way. Conductor Y, passing to the right from pole N, encounters a 30 magnetic flux generated by auxiliary pole s , which flux is of a sign opposite to that of pole N. The result is to cause a fall of the voltage in conductor Y which is a very abrupt one, as indicated, by way of one example, at B, D, E, in "Source," Fig. 4. The sharpness of that fall or drop of potential in conductor Y after it has left the regular field pole N may be controlled by varying the rheostat X^1 (and thereby varying the 35 strength of pole s and the flux density thereunder) or by varying the positions of pole s , as by making it adjustable or sliding either in the direction of arrow F or that of arrow G. Adjustment in direction F brings the 40 drop in voltage farther along the curve. Adjustment in direction G has the same effect as weakening the strength of the field of auxiliary pole s , i. e., causes the drop in voltage to be less steep.

As shown in Fig. 6, the special generator G, of any desired form for producing the 50 gradually charging asymmetrical potential wave, such as the form of Fig. 5, is connected to the step-up transformer T which is connected to the condenser structure 1 of the 55 exciter circuit. The discharge-gap structure is at 2, and the concentrated inductance at 3; and the entire sending apparatus is connected through the inductance 3 and terminals 4, 5, to any desired radiating system 60 or net-work, such as any of the various forms heretofore employed. The entire apparatus of Fig. 6 is designed, with the generator G, to produce the results hereinbefore 65 described, in respect not only to effi-

cency of waves radiated in proportion to energy supplied from the source G, but also to persistent and uniform single-frequency ether waves of uniform single wave-train frequency.

In Fig. 7 is shown the receiving apparatus or receiver, connected by terminals 6, 7, to any desired receiving system or network, such as any of the various forms heretofore employed. This receiver, as to its main circuit, is designed for cooperation with the above sender of Fig. 6 in particular respect to the above named features of persistent and uniform single-wave-frequency wave-trains. This main circuit includes the inductance 8 and the condenser 9 in series therewith, and is the only wave-tuned circuit of the receiver. There would be no advantage in a second wave-tuned circuit, used sometimes heretofore, on account of the fact that the 80 radiated wave-trains of my system are pure, i. e., of a single wave-frequency, so that only a single circuit is needed to receive them efficiently, the result of this being that sharp tuning and maximum efficiency in receiving 85 are obtained by such single wave-tuned receiving circuit. A second wave-tuned circuit is useful only to enable the combined circuits to receive as much as possible of the energy of complex ether waves such as are 90 indicated in Fig. 1. The wave-tuning of the main circuit of Fig. 7 is done by properly proportioning the inductance 8 and the capacity 9, so that the main circuit is tuned to the wave-frequency of the radiated waves. The same instruments 8 and 9 are also both 95 proportioned so that the decrement or persistency of the main circuit corresponds with the persistency of the transmitted wave-trains. Since the latter in my system have 100 high persistency, a large amount of inductance 8 may be included in the main circuit, as shown, and a correspondingly small capacity 9, in order to preserve the desired 105 wave-tuning and at the same time preserve 110 a low decrement.

The details of construction of the elements of the sender are shown in Fig. 6. The condenser 1 consists of a number of plates 10 of glass or other suitable dielectric, having conducting coatings 11 on both sides, preferably secured to the dielectric in accordance with United States patent to Pickard, No. 893,811, of July 21st, 1908. The plate form of condenser is particularly preferred in my 115 system, instead of the Leyden jar form, because it permits of such compact arrangement of the condenser-units that the inductance of the condenser connections to the other elements of the sender is very small, 120 this being an important consideration because it permits a maximum amount of the inductance of the sender to be concentrated in that major portion of inductance 3 which is common to both the radiator and exciter 130

circuits. In my shock or impact system such concentration in a common inductance is employed on account of its function, as constituting a "tight coupling" between the exciting and radiating circuits, in assisting the action of the discharge-gap in abruptly transferring the energy from one circuit to the other, and in coöperating with the special form of potential wave in eliminating extra discharges.

10 The condenser plates 10 are arranged relatively as shown, in a stack, preferably resting on edge and contained in an oil tank, not shown. The leads from the condenser units 15 are taken off from the conducting coatings 11, either in parallel as shown, or in series-parallel, depending upon the voltage and power employed.

15 The details of the air-cooled discharge-gap structure 2 are also shown in Fig. 6. That structure comprises a plurality of pairs of rings 12, 13, the number and size depending on the voltage and power employed, and the pairs being separated by conducting 20 (metal) pins 14. The rings of each pair are separated by peripheral and central gaskets 25 15 and 16 of insulating material, providing an inclosed construction for the discharge spaces 17 between the discharge surfaces 18. The rings 12, 13 are of copper, or of other 30 metal also having high thermal conductivity, in order to rapidly convey away from the discharge surfaces any heat which may be generated by the discharges.

35 The discharge surfaces 18 consist of silver annuli secured to the copper rings 12, 13 in any suitable way as by brazing, the silver having a thickness of about a sixteenth of an inch. Silver is preferred because it has 40 very high electrical and thermal conductivity and is not easily roughened or oxidized by the discharges. A most important feature of the construction is that which insures uniform cooling of the discharge 45 surfaces 18. A common passage 19 (closed at bottom 30) extends through the center of the pairs of rings 12, 13, this passage being connected to a pipe 20 in turn connected to an ordinary exhaust or pressure blower (not 50 shown) which causes circulation of air at low pressure. The effective cooling circulation is that through the transverse passages 21 formed between the pairs of rings 12, 13 by the pins 14, and branching from the central 55 passage 19. In operation, the air passes radially in all directions, either inward or outward through the passages 21, thereby conveying heat away from the surfaces of adjacent pairs of rings 12, 13 and thereby 60 keeping down the temperature of the silver discharge surfaces 18 which are in heat-conducting relation with the rings 12, 13. This system of cooling is absolutely uniform, so that all parts of the discharge 65 surfaces 18 are kept at equal temperature, the

important result of the cooling system and of this entire discharge structure generally being the elimination of any tendency of heat to cause a localization of successive and possibly irregular discharges at any one 70 point on a discharge surface, and generally the elimination of all conditions liable to result in irregular or extra discharges. Hence the discharge structure has an important function in coöperating with the 75 special form of potential wave employed, to eliminate all harmful extra and irregular discharges. This action of the discharger in assisting to insure regularity of discharges and consequent uniformity of wave- 80 frequency and train-frequency, makes it also useful as a means of preventing all oscillatory action in the exciter beyond a partial half-swing after the first or effective single complete half-swing, as shown at U, "Exciter", Fig. 4. Hence this discharger, which is useful as a means assisting to prevent all 85 irregularity of discharges, is also useful as an element of the preferred embodiment of my invention, *i. e.*, in the shock or impact 90 system hereof, wherein important elements are also the special potential wave, and particularly the tight coupling, via the concentrated inductance 3 (Fig. 6) between the exciter and the radiator, providing a free exit 95 for energy from the exciter to the radiator. Thus the combination of the described discharger, the special potential wave, and the tight coupling, constitute the chief elements 100 of my shock or impact sending system, 105 wherein the exciter is a true dead-beat, non-oscillatory circuit, all the energy in which, in the form of an instantaneously-existing partial swing preferably of the same non-interfering wave-form as that produced by 110 it in the radiator, is instantly expelled through the tight coupling to the radiator where it is thereafter isolated from the exciter.

110 In Fig. 6, the inductance 3 and its connections are shown diagrammatically as representing an inductance the major portion of which is common to the exciter and radiator circuits. Any suitable construction, in place 115 of the single coil structure shown, may be employed, particularly when the arrangement is such as to provide a tight coupling, described above as being of great importance in my system.

120 In Fig. 7 are shown the important details of the receiver circuits, including particularly the means for providing for the same train-frequency as that of the uniform or evenly spaced wave-trains which are radiated from the sender of this invention. The 125 detector 22 may be connected to the inductance 8 as shown, and is preferably of the rectifier type of the various inventions and United States patents of Greenleaf Whittier Pickard. This detector may be em- 130

ployed without any auxiliary source of voltage, but preferably a potentiometer 24 is used, consisting of a battery 25 and a resistance 26 with adjustable tap 27, the arrangement, particularly as to amount and direction of E. M. F., being as set out in Pickard United States Patent Number 912,613 of February 16th, 1909. The telephones 23, or other suitable indicating devices, are connected as shown. It is preferred to employ the telephone having a construction like that of Pickard United States Patent No. 972,715 of October 11th, 1910. The condenser 28 is connected, as shown, in shunt to the indicating device 23, and its capacity is so chosen, with relation to the inductance of the windings of device 23, that the circuit thus formed has a periodicity corresponding with the rate of discharge of the discharger 2 of Fig. 6. That is, if the special generator G of Fig. 6, illustrated in detail in Fig. 5, has a frequency of five hundred cycles per second, and the other elements are such that there are a thousand discharges per second in the discharge structure 2 of Fig. 6, *i. e.*, one regular discharge for each half-cycle of the potential wave, as in Fig. 4, then the circuit 28, 27, 23 of the receiver, Fig. 7, is so proportioned as to have a periodicity of one thousand per second. This exact proportioning of the receiver to the ether wave-train frequency is made possible for the first time in this invention, by virtue of the fact that by means of the inventions herein, the wave-train frequency is for the first time made pure or uniform, *i. e.*, the trains of waves are evenly spaced from each other. Any suitable means may be employed as the equivalent of that above specified, to proportion the receiver to the train-frequency of the ether-waves.

In Fig. 4, at "Source", a discharge (B, C) is indicated at each half-cycle of the potential wave. In some cases, however, it is advantageous to have only one discharge for each complete cycle, in which cases the discharge B, C is omitted and the discharge F, G (second half cycle, Fig. 8) is the only one for the complete cycle. This may be accomplished in various ways, as by reducing the field excitation of the generator G, Fig. 6, as by rheostat X, Fig. 5, to such a point that the voltage at B ("Source", Fig. 4) is below the break-down point of the discharge, and also preferably by employing a transformer at T (Fig. 6) having a high magnetic leakage (constituting a loose coupling between the generator and the condenser) so that the condenser is charged by pure resonance, thereby producing a rise of potential which first reaches at F ("Source", Fig. 8) a sufficient value to break down the discharger. This is advanta-

geous not only because the condenser is more efficiently charged (*i. e.*, sufficiently charged by a source of lower voltage), by a gradual application of potential, *i. e.*, by pure resonance charging, than by a more or less forced charge such as that by only a quarter cycle; but it is also advantageous because the time of occurrence of the single discharge F, G is most accurately fixed, *i. e.*, the purest or more uniform train-frequency is attained. Fig. 4 shows the discharge B, C after only a quarter-cycle charge of the condenser, from A to B. In Fig. 8 are shown the conditions of resonance-charging above referred to, as insuring a higher perfection of pure train-frequency *i. e.*, regular recurrence of condenser discharges. It is clear that in order to obtain the same train-frequency with one discharge per cycle as with two, the frequency of the generator G, Figs. 6 and 5, will be doubled.

In Fig. 8 are shown curves at "Source" and "Exciter" similar to the corresponding curves of Fig. 4, with an interpolated showing of "condenser" condition to illustrate the resonant charging of the condenser. At "Source," the portion A, B, E, F of the curve is preferably sinusoidal and no discharge occurs prior to that at F, G, and the part F, H, I, of the curve has the same feature of abrupt decline as has the part B, D, E of "Source," Fig. 4. The single resulting complete half oscillation, for each complete cycle of the potential wave, is shown at U, "Exciter," Fig. 8. Comparing the "source" curves of Figs. 4 and 8, the fact appears that the charging of the condenser in the latter case occupies three-quarters of a complete cycle of the potential wave, instead of one-quarter as in Fig. 4. The curve at "Condenser," Fig. 8, illustrates the resulting potential on the condenser (at 1, Fig. 6). In Fig. 4 no separate showing of the potential on the condenser is made because that potential is substantially identical with the curve at "Source," Fig. 4 (modified only by its discharge at B, C,) on account of the comparatively tight coupling between the generator and condenser constituted by a transformer T having small magnetic leakage, which tight coupling compels the condenser potential to closely follow the potential wave form of the source. As is shown at "Condenser," Fig. 8, the potential on the condenser in that case does not follow the potential wave form of the source, but, as at A¹, B¹, E¹, F¹ builds up gradually to a maximum value, reached at F¹, sufficiently high for discharge. The potential at the maximum point of the first half cycle, as at B¹, is far too low to permit a discharge there. For the same train-frequency, the generator frequency of Fig. 8 is twice that of Fig. 4, so that the time occupied by a

semi-cycle in Fig. 8, is only half of that in Fig. 4. For this reason, the maximum potential at F¹, "Condenser," Fig. 8, other things being equal, is by that measure located more accurately in point of time, so that a series of discharges U ("Exciter," Fig. 8) are more evenly spaced from each other. This asymmetrical potential wave of Fig. 8 is included in my definition, stated above, of the gradually charging asymmetrical wave of this invention. The precise sinusoidal form of the wave from A to F, Fig. 8, is not necessary, but it is preferred to approach that as nearly as possible, although a modification of the generator of Fig. 5 is necessary if this exact form of wave is to be obtained by a special construction of generator. If desired, the feature of prolonged or resonant charging, and single discharge per potential wave cycle, can be obtained by the use of the generator of Fig. 5 and its resultant potential wave at "source," Fig. 4, the drop B, D, E in the first half-cycle being merely a slightly inferior form, as to charging, of the curve at "Source," Fig. 8, and being a feature not affecting the object, *i. e.*, exact time-recurrence of the single discharge per cycle. This is attained in the same way, *i. e.*, by reducing the field excitation of the generator and preferably employing a transformer T (Fig. 6) having a high magnetic leakage, to provide a loose coupling between the generator and the condenser; no discharge being permitted in the first half-cycle of the potential wave because the gradual resonant charging of the condenser does not cause a sufficient potential to discharge, at the maximum of said first half-cycle.

The advantages of the invention disclosed herein have been above set forth, but the most important may be recapitulated as follows: The exciter circuit is divorced from the radiator as an element involved in the effective action of the radiator, and is restricted to the functioning of starting, at definitely recurring instants, the swinging of the radiator, the action of the exciter being to abruptly charge the radiator by shock or impact, and then stop acting, it being therefore a dead-beat circuit. The radiator, left free to swing by itself as to the energy supplied to and isolated in it, persistently oscillates, without interference by or with any other conductor, until all its energy is gradually or persistently imparted to the ether in the form of persistent trains of ether-waves. The regularity of action of the exciter and the independence of action of the radiator, produce the following advantageous results: First, the series of trains of oscillations and of resulting ether waves are uniform, *i. e.*, are evenly spaced apart, (and also of equal lengths), and the

receiver therefore has a single train-frequency which accurately corresponds to such single or pure train-frequency of the ether wave-trains; the result of this being maximum efficiency of receiving, in respect to train-frequency. Second, each train of oscillations and of resulting ether waves is simple, pure or uniform, *i. e.*, has only a single wave-frequency, lacking any complexity of frequencies or multiplicity of wave-trains combined in a single complex train; and therefore the receiver has only a single circuit (the antenna or net-work) which is tuned to the single or pure wave-frequency of the ether waves; the result of this being maximum efficiency in receiving, in respect of the wave-frequency. Third, each train of oscillations and resulting ether-waves has maximum persistency, the very important result of which is maximum efficiency in receiving, in particular respect of the receiving net-work, which is tuned to the ether-wave frequency and which therefore oscillates with a maximum persistency corresponding with the maximum persistency of the ether waves, with the ultimate result of efficiency of supply of energy to the indicating devices of the receiver. The gross effect of all the above is maximum efficiency between the sending generator and the indicating devices at the receiver, and also maximum efficiency of radiation and reception, which is indicated by the absolutely pure musical note given by the receiving telephones. The lack, in that note, of any rustling or hissing non-musical sounds, indicates the corresponding freedom of the ether waves from all impurities or lack of uniformity, and the measurable amount of energy which is received indicates that the single wave-tuned receiving circuit (the antenna or net-work) is receiving all the energy transmitted to the receiver, *i. e.*, that only pure and uniform ether disturbances are being transmitted, and indicates that the sending circuits are free from all theoretically preventable losses.

I claim:

1. In wireless signaling by electric ether waves, the method of preventing extra discharges which consist in impressing upon the exciting circuit of the sender, a gradually charging asymmetrical wave of potential, characterized by an ascending portion less steep than the descending portion.
2. In wireless signaling by electric ether waves, the method which consists in charging the exciter with a gradually charging asymmetrical potential wave, characterized by an ascending portion less steep than the descending portion, and charging the radiator with the energy of the exciter discharge.
3. In wireless signaling by electric ether

waves, the method which consists in charging the sender with a gradually charging asymmetrical potential wave, characterized by an ascending portion less steep than the 5 descending portion.

4. Means for charging a sending apparatus of a system of signaling by electric ether waves, and constructed and arranged to produce a gradually charging asymmetrical potential wave, characterized by an 10 ascending portion less steep than the descending portion.

5. Means for charging a sending apparatus of a system of signaling by electric ether waves, and constructed and arranged to charge the exciter with a gradually charging asymmetrical potential wave, characterized by an ascending portion less steep than the 15 descending portion.

20 6. Means for charging a sending apparatus of a system of signaling by electric ether waves, which consists of an alternating current generator constructed and arranged to supply to the exciter a gradually 25 charging asymmetrical potential wave, characterized by an ascending portion less steep than the descending portion.

7. Means for charging a sending apparatus of a system of signaling by electric ether waves, which consists of an alternating 30 current generator arranged to supply the exciter and having an auxiliary set of field poles respectively near its regular field poles and of opposite magnetic signs.

35 8. Means for charging a sending apparatus of a system of signaling by electric ether waves, which consists of an alternating current generator arranged to supply the exciter and having an auxiliary set of field 40 poles respectively near its regular field poles and of opposite magnetic signs, said auxiliary poles being adjustable in a direction to vary the location of the drop in voltage along the potential curve.

45 9. Means for charging a sending apparatus of a system of signaling by electric ether waves, which consists of an alternating current generator supplying the exciter and having an auxiliary set of field poles 50 respectively near its regular field poles and of opposite magnetic signs, said auxiliary poles being adjustable in a direction to vary the steepness of the drop in voltage in the potential curve.

55 10. In wireless signaling by electric ether waves, the method which consists in resonantly charging the condenser of the exciter circuit with a gradually charging asymmetrical potential wave.

60 11. In wireless signaling by electric ether waves, the method which consists in resonantly charging the condenser of the exciter circuit with a gradually charging asymmetrical potential wave, and causing one dis-

charge of the condenser for each complete 65 cycle of the wave.

12. In wireless signaling by electric ether waves, the combination with an exciter, of an alternating current generator supplying the exciter with current having a potential 70 wave form characterized by an ascending portion less steep than the descending portion, and a transformer having high magnetic leakage constituting a loose coupling between the generator and the exciter. 75

13. In wireless signaling by electric ether waves, the combination with an exciter, of means for producing a gradually charging asymmetrical potential wave characterized by an ascending portion less steep than the 80 descending portion, and a loose coupling between said exciter and producing means.

14. In wireless signaling by electric ether waves, the method which consists in charging the exciter by a gradually charging 85 asymmetrical potential wave characterized by an ascending portion less steep than the descending portion, preventing persistence of oscillations in the exciter, and charging the radiator by the impact of the abruptly 90 terminated action in the exciter.

15. In wireless signaling by electric ether waves, the method which consists in charging the exciter with current having a potential wave form characterized by an ascending 95 portion less steep than the descending portion and preventing extra discharges in the exciter, preventing persistency of oscillations in the exciter upon the discharge thereof, and charging the radiator by the 100 impact of the exciter oscillation and isolating the energy thereof from the exciter in the radiator.

16. In a shock or impact system of wireless signaling by electric ether waves, means 105 for preventing extra discharges of the exciter, which comprises the combination of a means for charging the condenser of the exciter with a gradually charging asymmetrical potential wave characterized by an 110 ascending portion less steep than the descending portion, with a discharger for the exciter, constructed to permit uniform cooling of its discharge surfaces.

17. In a shock or impact system of wireless signaling by electric ether waves, means 115 for preventing extra discharges of the exciter, which comprises the combination of a discharger constructed with a plurality of pairs of discharge surfaces with spaces between the pairs; with means for charging the exciter with a gradually charging asymmetrical potential wave, characterized by an ascending portion less steep than the 120 descending portion.

18. In a shock or impact system of wireless signaling by electric ether waves, means for preventing extra discharges of the ex-

- citer, which comprises the combination of a condenser-discharger consisting of a plurality of pairs of discharge surfaces with spaces between the pairs; with an alternating current generator constructed and arranged to supply the condenser with a gradually charging asymmetrical wave of potential, characterized by an ascending portion less steep than the descending portion.
19. In wireless signaling by electric ether waves, the combination with an alternating current generator constructed and arranged to produce a gradually charging asymmetrical potential wave; characterized by an ascending portion less steep than the descending portion of an exciter; a transformer having high magnetic leakage and constituting a loose coupling between the generator and exciter; said exciter including a condenser, a discharge structure including a plurality of discharge spaces and means for uniformly cooling the discharge surfaces; and a radiator tightly coupled to the exciter.
20. In wireless signaling by electric ether waves, the combination with a radiator, of an exciter comprising a battery of plate condensers, means for supplying the exciter with current having an asymmetric potential wave characterized by an ascending portion less steep than the descending portion, a discharge structure including a plurality of discharge spaces and means for uniformly cooling the discharge surfaces; and a means for preventing extra discharges in the exciter; and a concentrated inductance constituting a tight coupling between the exciter and radiator.
21. In wireless signaling by electric ether waves, the combination with a radiator, of an exciter; means for charging the exciter with a gradually charging asymmetrical potential wave; characterized by an ascending portion less steep than the descending portion, said exciter comprising a battery of plate condensers, a discharge structure including a plurality of discharge spaces and means for uniformly cooling the discharge surfaces thereof; and a concentrated inductance constituting a tight coupling between the exciter and radiator.
22. In wireless signaling by electric ether waves, the combination with an exciter; of means for supplying the exciter with a gradually charging asymmetrical potential wave; characterized by an ascending portion less steep than the descending portion, said exciter including a discharge structure including a plurality of discharge spaces and means for uniformly cooling the discharge surfaces; and a radiator tightly coupled to the exciter.
23. In wireless signaling by electric ether waves, the combination with a radiator; of an exciter comprising a battery of plate condensers, means for supplying the exciter with current having an asymmetric potential wave characterized by an ascending portion less steep than the descending portion, a discharge structure including a plurality of discharge gaps and means for uniformly cooling the discharge surfaces of said gaps; and a concentrated inductance constituting a tight coupling between the exciter and radiator.
24. In wireless signaling by electric ether waves, the combination with an exciter, of means for charging the exciter with a gradually charging asymmetrical potential wave characterized by an ascending portion less steep than the descending portion, said exciter including a discharge structure having a plurality of discharge gaps and means for uniformly cooling the discharge surfaces; a radiator; and a tight coupling between the radiator and exciter; all whereby the waves emitted from the radiator comprise a series of persistent trains of single uniform wave-frequency and single uniform train-frequency.
25. In wireless signaling by electric ether waves, the combination with an exciter which includes a plurality of discharge spaces and means for cooling the discharge surfaces; of means for preventing extra discharges in the exciter, said means including a source of current having an asymmetric potential wave characterized by an ascending portion less steep than the descending portion; a radiator; and a tight coupling between the exciter and the radiator.
26. In wireless signaling by electric ether waves, the combination with means for producing a gradually charging asymmetrical potential wave characterized by an ascending portion less steep than the descending portion, of a dead-beat exciter loosely coupled thereto; and a radiator tightly coupled to said exciter.
27. In wireless signaling by electric ether waves, the combination with a sender comprising a radiator and an exciter, of means for limiting the action of the exciter to substantially a single oscillation, said means including a source of potential of an asymmetric wave form characterized by an ascending portion less steep than the descending portion.
28. In wireless signaling by electric ether waves, the combination with a sender comprising a radiator and an exciter, of means for limiting the action of the exciter to substantially a single oscillation, said means including a source of potential of an asymmetric wave form characterized by an ascending portion less steep than the descending portion, and a tight coupling between the exciter and radiator whereby the energy

- of the exciter-oscillation is abruptly transferred to the radiator.
29. In wireless signaling by electric ether waves, the combination with a source of potential having an asymmetric wave form characterized by an ascending portion less steep than the descending portion, a dead-beat exciter, of a radiator, and a tight coupling between the exciter and radiator.
- 10 30. In wireless signaling by electric ether waves, the combination with an exciter including a discharge structure comprising a plurality of discharge spaces in series and means for uniformly cooling the discharge surfaces, means for supplying the discharge structure with a potential having an asymmetric wave form characterized by an ascending portion less steep than the descending portion, all whereby the discharge of the exciter is limited to substantially a single oscillation, and the exciter then open-circuited; and a radiator tightly coupled to the exciter, whereby the energy of the limited action of the exciter is abruptly transferred to the radiator; all whereby the ether waves emitted from the radiator have a single uniform wave-frequency.
31. In wireless signaling by electric ether waves, the combination with an exciter, of means for preventing the persistency of oscillations therein, means for preventing extra discharges therein, including a source of supply to the exciter of potential having an asymmetric wave form characterized by an ascending portion less steep than the descending portion, and a radiator tightly coupled to said exciter, whereby the series of trains of ether waves emitted from the radiator have a single uniform wave-frequency and a single uniform train-frequency.
32. In wireless signaling by electric ether waves, the combination with an exciter, a radiator tightly coupled thereto; means for limiting the action of the exciter to substantially a single oscillation for each discharge; and means for preventing extra discharges in the exciter; including a source of supply to the exciter of potential having an asymmetric wave form characterized by an ascending portion less steep than the descending portion, all whereby the ether waves emitted from the radiator have a single uniform wave-frequency and a single uniform train-frequency.
33. In wireless signaling by electric ether waves, the method which consists in charging a radiator by shock or impact at uniformly recurring instants, and isolating each such charge on the antenna to permit its complete radiation in uniform persistent trains of ether waves having a single uniform train-frequency and a single uniform wave-frequency, said isolation being con-
- tributed to by supplying an initial charge 65 in the form of a potential of asymmetric wave form characterized by an ascending portion less steep than the descending portion.
34. In wireless signaling by electric ether waves, the combination with an exciter, of means for limiting the excitation thereof to substantially a single oscillation, means of supplying the exciter with potential of an asymmetric wave form characterized by an ascending portion less steep than the descending portion, and a radiator tightly coupled to the exciter and caused thereby to operate with persistent oscillation-trains having a single uniform train-frequency and a single uniform oscillation-frequency.
35. In wireless signaling by electric ether waves, the method of producing ether waves of single uniform train-frequency and single uniform wave-frequency, which consists in charging the radiator by shock or impact at uniformly recurring instants, and electrically isolating the radiator from the charging means during the intervals between the 90 instants of charging, said isolation being contributed to by supplying an initial charge in the form of a potential of asymmetric wave form characterized by an ascending portion less steep than the descending 95 portion.
36. In wireless signaling by electric ether waves, the combination with means for producing a gradually charging asymmetrical potential wave, characterized by an ascending portion less steep than the descending portion, of an exciter connected therewith to be charged thereby, whereby the discharges therein are of a single uniform discharge-frequency; a radiator connected with said 105 exciter and in which the oscillation trains have a single uniform train-frequency corresponding with that of the discharges in the exciter, and from which are radiated trains of ether waves having a single uniform 110 train-frequency corresponding with the oscillation-trains in the radiator; and a receiver having a single uniform train-frequency corresponding with that of the radiated ether waves.
37. In wireless signaling by electric ether waves, the combination with an exciter, of means for applying thereto a gradually charging asymmetrical potential wave characterized by an ascending portion less steep 120 than the descending portion; a radiator coupled to the exciter, and thereby emitting trains of ether waves having a single uniform train-frequency; and a receiver having substantially the same single train-frequency.
38. In wireless signaling by electric ether waves, the combination with a radiator, of

means for causing the emission therefrom of wave-trains of a single uniform train-frequency, including a source of potential of asymmetric wave form characterized by an 5 ascending portion less steep than the descending portion, and a receiver having substantially the same train frequency as that of the ether waves.

39. In wireless signaling by electric ether 10 waves, the combination with an exciter, of means for preventing extra discharges in the exciter; including a supply of potential of asymmetric wave form characterized by an ascending portion less steep than the descending portion, a radiator tightly coupled to the exciter; and a receiver having a single uniform train-frequency substantially corresponding to the single uniform train-frequency of the ether waves emitted from the 20 radiator.

40. In wireless signaling by electric ether waves, the combination with an exciter, of means for limiting the action of the exciter to substantially a single oscillation for each 25 discharge; including a supply of potential of asymmetric wave form characterized by an ascending portion less steep than the descending portion, a radiator tightly coupled to the exciter; and a receiver having substantially the same single wave-frequency as that of the ether waves emitted from the 30 radiator.

41. In wireless signaling by electric ether waves, the combination with a radiator; of 35 means for causing the emission therefrom of wave-trains having a single uniform wave-frequency, including a supply of potential of asymmetric wave form characterized by an ascending portion less steep than the descending portion, and a receiver having substantially the same wave-frequency as that of the ether waves.

42. In wireless signaling by electric ether waves, the combination with a radiator, of a 45 receiver including a receiving antenna; means for causing the emission from the radiator of ether waves having a single uniform wave-frequency; including a supply of potential of asymmetric wave form characterized by an ascending portion less steep than the descending portion, and a single circuit of the receiver, namely the antenna, having the same wave-frequency as that of the ether waves.

43. In wireless signaling by electric ether 55 waves, the combination with an alternating current generator supplying a gradually charging asymmetrical potential wave characterized by an ascending portion less steep than the descending portion, of an exciter charged thereby and including a condenser and a plurality of discharge gaps and means for cooling the discharge surfaces thereof; a radiator, an inductance constituting a tight

coupling between the radiator and exciter; 65 and a receiver having the same train and wave-frequencies as the single train and single wave-frequencies of the ether waves emitted from the radiator.

44. In wireless signaling by electric ether 70 waves, the combination with an exciter, of means for applying thereto a gradually charging asymmetrical potential wave characterized by an ascending portion less steep than the descending portion; a radiator; an 75 inductance constituting a tight coupling between the exciter and radiator; said exciter including a plurality of discharge gaps and means for uniformly cooling the discharge surfaces, all whereby the trains of waves 80 emitted from the radiator have a single uniform train-frequency and a single uniform wave-frequency; and a receiver having substantially the same single train-frequency and the same single wave-frequency. 85

45. In wireless signaling by electric ether waves, the combination with means for producing a gradually charging asymmetrical potential wave characterized by an ascending portion less steep than the descending 90 portion, of an exciter connected therewith to be charged thereby, whereby the discharges therein are of a single substantially uniform discharge-frequency; means for making said exciter dead-beat; a radiator 95 connected with the dead-beat exciter and in which the oscillations and the oscillation-trains have, respectively, single uniform oscillation- and train-frequencies, and from which ether waves are radiated which have 100 single uniform wave- and train-frequencies corresponding with the frequencies of the radiator, and a receiver having a single train-frequency, and a single wave-frequency, respectively, corresponding with the 105 single uniform wave- and train-frequencies of said ether waves.

46. In wireless signaling by electric ether waves, the combination with an exciter, of means for limiting the action of the exciter 110 to substantially a single oscillation for each discharge; means for preventing extra discharges in the exciter; including a source of potential of asymmetric wave form characterized by an ascending portion less steep 115 than the descending portion, a radiator tightly coupled to the exciter; and a receiver having substantially the same single uniform wave- and train-frequencies, respectively, as the single uniform wave- and 120 train-frequencies of the ether waves emitted from the radiator.

47. In wireless signaling by electric ether waves, the combination with a radiator, of means for causing the emission therefrom of 125 ether waves having a single uniform wave frequency and a single uniform train frequency; including a source of potential of

asymmetric wave form characterized by an ascending portion less steep than the descending portion, and a receiver having substantially the same single train- and wave-
5 frequencies respectively.

48. In wireless signaling by electric ether waves, the combination with a radiator, of means for causing the emission therefrom of ether waves having a single uniform wave-
10 frequency and in the form of persistent trains, including a source of potential of

asymmetric wave form characterized by an ascending portion less steep than the descending portion, and a receiver having an antenna having a correspondingly low decrement and substantially the same single wave-frequency as that of the uniform ether-wave frequency. 15
